(57) **CLAIM**

We claim the ornamental design for a cutting tool, as shown.

DESCRIPTION

FIG. 1 is a front and side perspective view of a cutting tool showing our new design;

FIG. 2 is a rear and side perspective view thereof;

FIG. 3 is a right side elevation view thereof;

FIG. 4 is a top plan view thereof;

FIG. 5 is a left side elevation view thereof;

FIG. 6 is a bottom plan view thereof;

FIG. 7 is a front elevation view thereof; and,

FIG. 8 is a rear elevation view thereof.

The dashed line showing of the scissors is included for purposes of environment and forms no part of the claimed design.
